A. A. GLISSON.

PACKAGE BINDER AND HOOKS THEREFOR AND RECORD CHECK.
APPLICATION FILED JULY 9, 1921.

1,396,190.

Patented Nov. 8, 1921.

UNITED STATES PATENT OFFICE.

AMOS A. GLISSON, OF FORT WORTH, TEXAS.

PACKAGE-BINDER AND HOOKS THEREFOR AND RECORD-CHECK.

1,396,190.

Specification of Letters Patent.

Patented Nov. 8, 1921.

Application filed July 9, 1921. Serial No. 483,501.

To all whom it may concern:

Be it known that I, AMOS A. GLISSON, a citizen of the United States of America, residing at Fort Worth, in the county of Tarrant and State of Texas, have invented certain new and useful Improvements in Package-Binders and Hooks Therefor and Record-Checks, of which the following is a specification.

My invention relates to an improved strap-binder, hooks and straps therefor, and a record check; and the object is to provide simple, effective and relatively economic means for closely and securely binding metal or other bands or straps about or around and protecting the contents of boxes, bales, trunks and the like when such articles are to be shipped or otherwise subjected to frequent or rough handling, and to afford means for preventing pilfering from shipping containers in the course of transportation; to provide means whereby persons to be held responsible for such containers and their contents in course of movements may be systematically and unerringly charged therewith when anything has been wrongfully done with such containers; to provide means for definitely identifying and promoting prompt and proper deliveries of shipments that may go astray. Another object is to provide devices by which packages or bales or containers may be quickly bound and to provide devices which are adjustable to several sizes of bundles, bales or containers. Other objects and advantages will be fully explained in the following description and the invention will be more particularly pointed out in the claims.

Reference is had to the accompanying drawings which form a part of this application.

Figure 1 is a perspective view of a package bound with one of the improved fastening devices. Fig. 2 is a side elevation or view of the tubular fastening device or sealing member. Fig. 3 is a plan view of the same. Fig. 4 is a longitudinal section of the same,—showing the interior locking members. Fig. 5 is a side elevation or view of the main locking member,—and Fig. 6 is a plan view of same. Fig. 7 is a side elevation or view of the stop member for one end of the band or strap,—and Fig. 8 is a plan view of the same. Fig. 9 is a detail view,—illustrating the manner of forming

the hooks on the ends of the band or strap,—which is to be secured by the fastening devices.

Similar characters of reference are used to indicate the same parts throughout the several views.

The locking device has a tubular member 1 which is larger at one end than at the other end and has a separable tag or check member 2 at the smaller end, the metal being perforated at the juncture of the tag member with the body of the member 1. The main locking member 3 has flanges 4 at right angles to the body thereof which serve as wall braces for the member 1 and as guard members for the ends of the securing band or strap 6 used for binding the packages, articles or containers to be protected. The locking member 3 has a turned-under extension at one end to form a hook 5 to engage the hook 13 of the securing band 6 within the tubular device 1. The other end of the member 3 has an extension which is preferably manifolded upon itself to form a cushioning member 7 and a hook 8,—the hook 8 being for locking the member 3 within the tubular member 1. The cushion member 7 will cause the band 6 to enter the upper part of the tubular member 1 so that the hook 9 of the band will be in position to engage one of the stops 10 of the locking or stop member 11. The locking member 11 is preferably made of a single piece of pliable metal and is preferably formed by devices that will cut the material to compose same to proper dimensions and cut or otherwise produce transverse slots therein and then form the stop member 10 by pressing the slotted portions of the strips of metal into stops or loops 10 to closely fit within the slot 12,—and pressing or forming flanges 14 on the edges of the stop member 11. The loop or stop members 10 will thus project through the slot 12 in the member 3 and the flanges 14 of the stop member 11 will rest against the bottom of the member 3 to hold the loop members 10 against movement relative to member 3. The hook 9 may engage any one of the loops 10,—the particular member to be engaged being determined in adjusting the band to size and character of package or bundle to be protected.

Preferably the locking member 3 is made of comparatively stiff but springy or resili-

ent metal and the manifolded or cushioning member 7 thereof is so formed, tempered and constructed that it serves the doubly co-operative purpose of keeping the stops or loops 10 pressed close to the upper part of the tubular member 1 and, by reason of its restricted springiness or resiliency, the member 7 will permit a yielding of the member 3 so that the member or hook 9 can be readily and easily adjusted to any one of the loops 10 for the purpose of binding the band 6 more or less tight about a package. Fig. 9 illustrates the construction of the hook formed on the ends of the securing band. The hook is made strong by doubly manifolding the metal upon itself. The folded portions 15 and 18 serve to brace the hook 13. The character of the folded portions 15 and 18 is such that when in adjustment within the tubular device they are strongly co-operative and new in effect in that they constitute a leverage,—effectively preventing the withdrawal or extraction of the binding bands even in cases where unusual or extreme force might be applied. This is on account of the closely adjusted positions they are forced to occupy between the stops 10 and the upper inner-portions of the tubular device 1 and the locking member 3 which is supported on the floor of the tubular device 1,—and because the manifolding of the portion of metal forming the hook itself strengthens its resisting influence and the adjustment of its extreme end between or within its manifolded-head, and as between the manifolded-head and the stop 10 and the upper inner-portion of the tubular device 1, is such that effort to withdraw the band will serve to expand and further tighten the hook-head within the device 1 and to most strongly prohibit such withdrawal.

Figs. 2, 3, and 4 illustrate the tag feature of the locking device:—The metal of the tube 1 may be extended in the form of a flat tag member 2 and numerals or letters entered thereon and the same numerals or letters entered on the body of the tubular member 1. The tag member 2 may be detached from the tubular device 1 after the shipment or package is sealed and be sent to destination, or, as a check for baggage or the like, may be carried by the owner of trunk, valise or package, for use in identifying the property at destination also for detecting it if it goes astray.

The tubular device 1 is provided with means for tightening the band or strap 6:—a perforation 16 being provided in the member 1 and a plurality of perforations 17 being made or provided in the band or strap 6. By using a pair of specially constructed pliers or other tool with one part inserted in the perforation 16 and the other part inserted in one of the perforations 17, the

band 6 can be drawn taut so that the hook 9 may be caught by the proper stop 10.

Various changes in the sizes, proportions, construction and arrangement of the several parts may be made without departing from my invention as set forth in the appended claims.

What I claim, is,—

1. A tubular locking device having means therein for securing and holding the ends 75 of a band or strap thrust therein and spaces on the exterior for identifying numbers and letters and having a flat extension from one side and perforated at the juncture with said tubular device and having space for 80 numbers and letters which are duplicates of the numbers and letters on said tubular device.

2. A tubular locking device having means therein for securing and holding the ends 85 of a band or strap thrust therein and a band or strap having the ends manifolded and hooks formed thereon for engaging said securing and holding means.

3. A tubular locking device having a locking 90 member mounted therein and provided with a hook on one end, a stop member detachably connected to said locking member and provided with a plurality of stops, and a band provided with hooks on the ends thereof 95 for engaging one of said stops at one end and for engaging the hook on the end of said locking member.

4. A tubular locking device having a locking member mounted therein, said locking member 100 having a hook on one end for engaging a band or strap and having on the other end a hook for engaging said tubular locking device and provided with a longitudinal slot therein, a stop member mounted in 105 said slot and detachably connected to said locking member and provided with a plurality of stops, and a band with a hook on one end for engaging the hook on said locking member and having a hook at the 110 other end for engaging one of said stops.

5. A tubular locking member device having a tapering form and a detachable locking member mounted therein with bracing flanges provided at the sides thereof,—and having on one end a hook for engaging a band or strap and having on the other end a hook for engaging said tubular locking device; a cushioning member, a stop member detachably connected to said detachable locking member and provided with a plurality of loops or stops, and a band or strap provided with hooks on the ends thereof,—one for engaging the hook on said detachable locking device and the other for engaging one of said loops or stops, said cushioning device permitting the end of the band to be thrust past said stops and between the stops and the upper side of said tubular locking device.

6. A tubular locking device having a slot in the exterior side and having a perforation for a clamping device, means therein for securing and holding the ends of a band 5 or strap thrust therein including a plurality of stops and a hook, and a band having a catch on one end for engaging said hook

and having a hook on the other end for engaging one of said stops and having perforations therein for a clamping instrument 10 for tightening the band about the package.

In testimony whereof I set my hand, this 6th day of July, 1921.

AMOS A. GLISSON.
